US00D880440S

(12) **United States Design Patent** (10) Patent No.: **US D880,440 S**
Green et al. (45) Date of Patent: ** Apr. 7, 2020

(54) **ELECTRONIC DEVICE**

- (71) Applicant: **Amazon Technologies, Inc.**, Seattle, WA (US)
- (72) Inventors: **Christopher Green**, San Francisco, CA (US); **Marc Rene Walliser**, San Francisco, CA (US); **Matthew Michael Seflic**, San Jose, CA (US)
- (73) Assignee: **Amazon Technologies, Inc.**, Seattle, WA (US)
- (**) Term: **15 Years**
- (21) Appl. No.: **29/694,199**
- (22) Filed: **Jun. 7, 2019**

Related U.S. Application Data

- (62) Division of application No. 29/609,169, filed on Jun. 28, 2017, now Pat. No. Des. 855,028.

CLAIM

The ornamental design for an electronic device, as shown and described.

DESCRIPTION

FIG. 1 is a top perspective view of an electronic device

FIG. 2 is a bottom perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the electronic device that form no part of the claimed design.

1 Claim, 8 Drawing Sheets
